UNITED STATES PATENT OFFICE.

WILLIAM BENDER, OF NEW YORK, N. Y.

MOLD-CLAMP.

1,168,147.

Specification of Letters Patent.

Patented Jan. 11, 1916.

Application filed August 24, 1915. Serial No. 47,066.

To all whom it may concern:

Be it known that I, WILLIAM BENDER, a citizen of the United States, and a resident of the city of New York, Winfield, borough 5 of Queens, in the county of Queens and State of New York, have invented a new and Improved Mold-Clamp, of which the following is a full, clear, and exact description.

10 The invention relates to molds for forming concrete columns and similar structures.

The object of the invention is to provide a new and improved mold clamp, which is simple and durable in construction, can be 15 easily applied for securely holding the mold sides in position against spreading.

In order to accomplish the desired result, use is made of angular plates adapted to fit onto the corners of the mold and having 20 their leg members fitting the sides of the mold, the leg members on each mold side overlapping one the other, and the said members being provided with slots extending in the direction of the length of the 25 members, the slots of the overlapping members being in register, and a bolt passing through the registering slots of each pair of overlapping members to adjustably fasten the members together.

30 A practical embodiment of the invention is represented in the accompanying drawings forming a part of this specification, in which similar characters of reference indicate corresponding parts in all the views.

35 Figure 1 is a plan view of the clamp as applied to a mold for forming a square concrete column; Fig. 2 is a side elevation of the same; and Fig. 3 is an enlarged sectional side elevation of the same on the line 3—3 40 of Fig. 1.

The four-sided mold shown in the drawing has each side formed of planks 10 connected with each other by cross boards 11 to hold the planks 10 for each mold side together. The clamp for this four-sided mold 45 consists of four horizontally disposed angular plates 12, alike in construction and each fitting exteriorly onto a corner of the mold, as plainly shown in Figs. 1 and 2. Each 50 angular plate 12 has its leg members 13 and 14 extending exteriorly along the sides of the mold and the said members are of sufficient length for the members of each side of the mold to overlap each other. The members 55 13 and 14 of each plate 12 are provided with lengthwise extending slots 15 on each

side of the mold and in register with each other, and through the registering slots passes a bolt 16 adjustably fastening the overlapping members on each mold side together. It will be noticed that on loosening the bolt 16 the angular plates 12 can be shifted inward and outward to fit the corresponding sides of the mold, and when the plates snugly embrace the mold sides then 60 their members 13 and 14 are securely fastened together by the bolt 16 to prevent the plates from coming apart and thus holding the mold sides 10 against spreading.

In practice, any number of clamps may be 70 used according to the height of the mold, and the lowermost plates 12 are preferably rested on the corresponding cross boards 11, as plainly indicated in Figs. 2 and 3. In order to prevent accidental lateral shifting of 75 the angular plates 12 one relatively to the other, the contacting faces of the overlapping members 13 and 14 are provided with lengthwise extending ridges and grooves 17 and 18, of which the ridges 17 of one member fit into the grooves 18 of the other member, as will be readily understood by reference to Fig. 3. When using the mold clamp on molds for forming columns of other polygonal shape, such as five-sided, six-sided 80 or eight-sided columns, then the members 13 and 14 of each plate 12 are arranged according to the angle of adjacent mold sides but otherwise the construction and use of the plates remains the same as above described. 85

It will be noticed that the mold clamp can be readily placed in position for holding the mold sides against spreading, and after the column is formed the plates can be readily 90 disconnected and removed for the removal of the sides 10 of the mold.

Having thus described my invention, I claim as new and desire to secure by Letters Patent:

1. A mold clamp, comprising a plurality of angular plates adapted to fit onto the corners of the mold and having their members fitting the sides of the mold, the members on a mold side overlapping one the other, the members being provided with slots extending in the direction of the length of the members, the slots of the overlapping members being in register, means extending through the slots for fastening the members together the contacting faces of the overlapping members being provided with 105 110 115

lengthwise extending ridges and grooves, the ridges of one member fitting into the grooves of the mating member.

2. In combination, a mold having each side 5 formed of planks having cross boards attached thereto, angular plates resting on the cross boards and fitting snugly onto the corners and against the sides of the mold, the members of each plate extending along adjacent sides of the mold and the said members 10 on a mold sidelapping one over the other in a common plane, means for fasten-

ing the overlapping members in adjusted position, said members having their contacting faces provided with interengaging longitudinally extending ridges. 15

In testimony whereof I have signed my name to this specification in the presence of two subscribing witnesses.

WILLIAM BENDER.
